Specification for Design.

Patented Oct. 8, 1912.

Application filed August 23, 1911. Serial No. 645,665. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Pendant-Fixtures, of which the following is a specification.

The nature of my design is fully illustrated in the accompanying drawing, to which reference is made, and in which,

Figure 1 represents an elevation of the design, and Fig. 2 a top plan view thereof.

My design comprises an inverted cup-like

pendant, the periphery of which flares outwardly in opposite directions from an intermediate portion in generally curved lines and terminates in a generally cylindrical flanged portion, having the contour and relative proportion of parts shown.

I claim:

The ornamental design for a pendant fixture as shown and described.

LINDSLEY SCHEPMOES.
